UNITED STATES PATENT OFFICE.

VICTOR T. HOEFLICH, OF NEW YORK, N. Y.

DESIGN FOR A WREATH.

Application filed April 6, 1928. Serial No. 26,154. Term of patent 14 years.

To all whom it may concern:

Be it known that I, VICTOR T. HOEFLICH, a citizen of the United States, and a resident of the borough of Bronx, city of New York, county of Bronx, and State of New York, have invented a new, original, and ornamental Design for a Wreath, of which the following is a specification, reference being had to the accompanying drawing, forming a part thereof.

The figure of said drawing is an elevational view of a wreath showing my new design.

I claim:

The ornamental design for a wreath, as shown.

VICTOR T. HOEFLICH.
